UNITED STATES PATENT OFFICE.

GEORGE C. ANDREWS, OF MINNEAPOLIS, MINNESOTA.

ROCKING GRATE.

No. 868,832.

Specification of Letters Patent.

Patented Oct. 22, 1907.

Application filed March 22, 1906. Serial No. 307,374.

To all whom it may concern:

Be it known that I, GEORGE C. ANDREWS, a citizen of the United States, residing at Minneapolis, in the county of Hennepin and State of Minnesota, have invented certain new and useful Improvements in Rocking Grates; and I do hereby declare the following to be a full, clear, and exact description of the invention, such as will enable others skilled in the art to which it appertains to make and use the same.

10 This invention has for its object to provide an improved grate especially adapted for use in connection with upright boilers such as used in hot water and steam heating systems, and to this end it consists of the novel devices and combinations of devices hereinafter described and defined in the claims.

The invention is illustrated in the accompanying drawings, wherein like characters indicate like parts throughout the several views.

Figure 1 is a horizontal section taken through a boiler 20 on the line $x^1 x^1$ of Fig. 2, and showing my improved grate applied thereto, some parts being broken away; and Fig. 2 is a vertical section taken through the boiler on the line $x^2 x^2$ of Fig. 1, the upper portion of the boiler being broken away.

25 The numeral 1 indicates the outer shell of the boiler, the same being of cylindrical form and having the usual door opening 2 in one side of its lower portion, which opens into the ash pit 3.

The numeral 4 indicates the inner shell or fire-box 30 of the boiler between which and the outer shell of the boiler the water chamber 5 is formed, the lower portion of said inner shell 4 being spaced apart from the shell 1, by means of the usual mud ring 6.

My improved grate involves an expandable and contractible grate supporting ring 7 preferably formed in two sections the ends of said sections being overlapped and having coincident circumferentially extended slots 8 through which nutted bolts 9 are passed. Each ring section has a pair of supporting feet 10 that extend 40 radially outward therefrom, and at their extremities are turned downward and are adapted to be rigidly but detachably secured to the boiler shell 1, by nutted bolts 11. The grate proper is made up of two long toothed grate bars 12, and two or more relatively short toothed 45 grate bars 13. The long grate bars 12 have short trunnions 14, and long trunnions 15 that rest in notches or open seats 16 formed in the sectional supporting ring 7. The said long trunnions 15 are also passed outward through perforations in the outer shell 1, and terminate 50 in angular portions 15^a to which a detachable shaker lever (not shown) is adapted to be applied. The short grate sections 13, at both ends, have short trunnions 17 that rest in notches or open seats 18 formed in the sectional supporting ring 7. The long grate sections 55 12 are provided with depending arms 19 and the short

grate sections 13 are provided with similar depending arms 20. The arms 19 of the long grate sections are connected by links 21 in the arms 20 of the short grate sections 13 that are on the same side of the center of the complete grate, and of the supporting ring 7. The connected arms 19 and 20 expand parallel to each other, so that when one of the long grates 12 is rocked, a corresponding rocking movement will be imparted to the short grate on the same side therewith. It will thus be seen that one half of the complete grate will be moved 60 by rocking one of the long grates, and that the other half of the grates will be moved by rocking of the said long grates. When the grate supporting ring 7 is secured in the working position shown in the drawings, the grate sections may be removed individually from 70 working positions, or placed individually in working positions. The short grates may be raised directly upward from and out of their seats and the grate supporting ring, but to remove the long grates, one end thereof must be raised and a slight endwise movement 75 imparted thereto, in order to withdraw the long trunnions 15 from the perforations in the shell 1. As shown, the links 21 are detachably pivoted to the arms 19 and 20 by means of pins 22 that are held in place by cotters 23.

In applying the grate supporting ring 7 in working position, or in removing it therefrom, the nutted bolts 9 are loosened, so that the two ring sections can be forced together or contracted, thereby carrying the feet 10 away from the inner surface of the boiler shell 1, 85 thus making it an easy matter to move said ring vertically within the ash pit portion of the boiler. In the application or removal of the said ring after the boiler is set up, it is necessary to remove the nutted bolts 9, thereby disconnecting the sections of the said ring, so 90 that they may be passed separately through the door opening 2. When the said ring is placed in working position, and its feet 10 are secured to the boiler shell 1 by means of the nutted bolts 11, the nutted bolts 9 should be tightened, thereby firmly clamping together 95 the overlapped ends of the sections of said ring.

In the construction of boilers having cylindrical shells, it usually happens that the said shells are not perfectly cylindrical or round in cross section. The expandable and contractible grate supporting ring, however, makes it possible to securely clamp the supporting feet thereof, against the surface of a boiler shell that varies considerably in cross section from true cylindrical form.

The perforations in the shell 1 through which the long trunnions 15 of the grate sections 12 are passed, are necessarily made considerably larger than the said trunnions, so as to permit the grates to be inserted by an endwise rocking movement, as above described. To keep the joint around the said trunnions tight, I pref- 110

erably provide a flexible thin metal plate 24 which is secured to the exterior of the shell 1, and the perforations of which closely fit the said trunnions 15.

This improved grate is of small cost, may be very easily and quickly applied in working position or removed therefrom, and when placed in working position, affords an extremely efficient grate. The fact that only one half of the grate is moved at one time in shaking down the ashes, gives the least possible disturbance to the bed of coals, and furthermore, makes the grate very easy to operate.

What I claim is:

1. The combination with a boiler having an approximately cylindrical fire box, of a sectional circumferentially expansible grate supporting ring, legs or spacing projec-

tions connecting the sections of said ring to the said boiler, of a plurality of toothed grate bars mounted on and supported by said supporting ring, substantially as described.

2. The combination with a cylindrical boiler, of a sectional grate supporting ring 7 having supporting feet 10 and overlapped ends formed with slots 8, nutted bolts working through said slots 8 for clamping the overlapped ends of said grate sections together, and a plurality of toothed grate sections 12 and 13 detachably mounted on and supported by said supporting ring 7, substantially as described. 20 25

In testimony whereof I affix my signature in presence of two witnesses.

GEORGE C. ANDREWS.
